ALENDO MCKENNEY, OF PORTLAND, AND SETH CARPENTER, OF PATTEN,
MAINE.

Letters Patent No. 66,099, dated June 25, 1867.

IMPROVED BOOT-LACING DEVICE.

The Schedule referred to in these Letters Patent and making part of the same.

TO ALL WHOM IT MAY CONCERN:

Be it known that we, ALENDO MCKENNEY, of Portland, Cumberland county, and SETH CARPENTER, of Patten, Penobscot county, all in the State of Maine, have invented an improved Boot-Lacing Device; and we do hereby declare that the following, taken in connection with the drawings which accompany and form part of this specification, is a description of our invention sufficient to enable those skilled in the art to practise it.

The invention relates to the construction and operation of a detachable device to be applied to that class of boots which "lace," for the purpose of enabling the lacing to be more easily tightened and loosened when the boot is upon the foot, such device consisting of a loose ring connected by a link to a button, each ring and link being inserted through the "upper" at a suitable distance from the laced edge, and being pressed through to the edge, between the lining and vamp, leaving the series of rings projecting from the opposite edges to be laced, each ring being loosed with respect to the link, but held in position relatively to the edge of the boot by the button at the opposite end of the link. Through a series of these rings the lacing is passed, it being carried from side to side and from ring to ring, as in the ordinary manner of lacing through holes punched through the edges to be brought together.

It is in the construction and employment of such a device that our invention consists.

The drawing represents a boot having our device applied thereto, a detail view showing the device separated from the boot.

a denotes a button or head, having a long link or eye, *b*, fixed to its under side. To this link, a ring, *c*, is applied, the ring hanging loosely therefrom. In the outer leather or vamp *d*, at each opposite side of the boot opening *e*, holes *f* are made, as seen, where one of the buttons is broken off, each hole extending through the vamp, and being of a size sufficient to admit the link and its ring, or so that the link and ring may be passed through it, and between the vamp and the lining to the edge, as shown in the drawing, the button holding the link in place, and a space at the edge being left unstitched for each link and ring, as will be readily understood. (The ring may, however, be made with provision for slipping it on to the link after the link is inserted.) When the rings are thus attached to the boot the lacing or lacings are run through them, as shown in the drawings. The boot being now placed on the foot, (the lacing being loosened,) the upper end of the lacing is drawn up, and it will readily be seen that the rings being loose they assume position in accordance with the gradual straightening of the lacing as the opposite edges of the boot are drawn together, and the strain produced thereby, and that by simply drawing upon the lacing at the top of the boot the lacing will readily render through all the rings instead of having to draw upon it gradually, or at every lacing hole or every few holes, as in the common method of lacing. When a pair of boots is worn and discarded the buttons and rings may be detached from said boots and placed in another pair, and being very strong they may be made to wear for a great length of time.

Now we are aware that metal eyes or loops for lacing have been fastened permanently to boots, but besides being expensive from the fact that being undetachable they had to be thrown away when the boots were worn out, the eye part in each was made removable relatively to the edge of the boot, and having a fixed angle of projection from such edge it could not yield in position to the varying position of the lacing or from the very zigzag position of the lacing when loose, to its gradually straightening position when tightened, and hence there was too great friction when trying to draw it through all the eyes or loops simultaneously to enable it to render freely, whereas with our device, as the rings are loose, they all yield to the direction of strain upon them.

We claim a shoe-lacing device constructed to operate substantially as set forth.

ALENDO MCKENNEY,
SETH CARPENTER.
